DRAFT RIGGING

Harvey J. Lounsbury, Glen Ellyn, Ill., assignor
to W. H. Miner, Inc., Chicago, Ill., a corpora-
tion of Delaware

Application May 25, 1932. Serial No. 613,414

5 Claims. (Cl. 213—9)

This invention relates to improvements in draft riggings especially adapted for use in connection with mine cars.

One object of the invention is to provide a 5 draft rigging, of simple and efficient design, having higher capacity in buff than in draft and wherein part of the shock absorbing means of the buffing mechanism is also employed to take the draft shocks, thereby economizing in the 10 total number of shock absorbing means necessary for the equipment of a car.

Another object of the invention is to provide a center buffer of high capacity for the end of a mine car, wherein the high buffing capacity 15 is obtained through the use of a plurality of shock absorbing springs, which are compressed against the end of the car by a single buffing head, and wherein certain of the shock absorbing 20 springs of the buffing means are made available to absorb draft shocks by compressing the shock absorbing springs against the buffing head.

Other objects of the invention will more clearly appear from the description and claims hereinafter following.

25 In the drawings, forming a part of this specification, Figure 1 is a broken away, horizontal, sectional view through one end of a mine car, illustrating my improvements in connection therewith. Figure 2 is an end elevational view, 30 partly broken away, looking toward the right in Figure 1. Figures 3 and 4 are horizontal, longitudinal, sectional views, corresponding respectively to the lines 3—3 and 4—4 of Figure 2. And Figures 5 and 6 are vertical, longitudinal, 35 sectional views, corresponding respectively to the lines 5—5 and 6—6 of Figure 1.

In said drawings, 10 designates the floor of a mine car, 11 the end wall, and 12 the end sill. As clearly shown in Figure 6, the end sill 12 is 40 of angular cross section and is riveted or otherwise secured to the end wall 11.

My improved draft rigging is applied to the end of the car as a unit and comprises a buffing head A, a supporting member B secured to the 45 end wall of the car, a transversely disposed draft beam C, upper and lower pairs of coil spring members D—D and E—E, and a coupling link F connected to the draft beam C.

The supporting member B comprises top and 50 bottom, horizontally disposed, spaced arms 13—13 connected by a vertical end wall 14. As most clearly shown in Figure 1, the end wall 14 extends laterally beyond the opposite sides of the arms 13—13. The end wall of the supporting member B is secured to the vertical end wall

11 of the mine car by any suitable means, such as rivets 15 and 16 extending through the walls 11 and 14. As shown, the rivets 16 also extend through the vertical flange of the end sill member 12. The end wall is also provided with a 60 forwardly projecting, horizontally disposed shelf 17 midway between the top and bottom arms 13—13, as clearly shown in Figure 5. The shelf 17 serves as supporting means for guiding the transversely disposed draft beam C in its movements.

The buffing head A has a vertical outer end wall 18 provided with a transversely curved, outer buffing surface which cooperates with a similar buffing head A on the adjacent car. The buffing 70 head A has top and bottom walls 19—19 and vertical side walls 20—20 extending rearwardly from the outer end wall 18 thereof. A hollow buffing head is thus provided, within which the spring shock absorbing members D—D and E—E are 75 housed. The top and bottom walls 19—19 are accommodated between the top and bottom arms 13—13 of the supporting member B, the buffing head A being thus in effect telescoped within the supporting member.

The draft beam C has a transverse rear end wall 22, which normally bears on the end wall 14 of the supporting member B. Relatively short top and bottom walls 23—23 and relatively short vertical side walls 24—24 extend forwardly from the wall 22. At the center, the top and bottom walls 23—23 of the draft beam C are enlarged so as to provide 85 forwardly projecting sections 25—25, which overlap rearwardly projecting sections 26—26 on the top and bottom walls 19—19 of the buffing head A. 90 The overlapping sections 25—25 of the draft beam C and 26—26 of the buffing head A are slotted, as indicated at 27—27 and 28—28 respectively, to accommodate vertically arranged connecting bolts 29—29, which are secured to the bottom and top arms 13—13 of the supporting member B.

The slots 28—28 of the buffing head A are so arranged that the buffing head is normally held against outward movement, but inward movement thereof is permitted during a buffing action. 100 The slots 27—27 of the draft member C are so arranged as to permit the necessary outward movement of the draft member. As shown in Figure 3, the adjacent ends of the side walls of the buffing head A and the draft member C are normally spaced apart so as to allow for the necessary relative movement of these two members.

The shock absorbing springs D—D and E—E oppose inward movement of the buffing head A when buffing shocks are transmitted to the buff- 110

ing head. The springs D—D are arranged above the springs E—E and also resist outward movement of the draft beam C during a draft action. In other words, the springs D—D and E—E are arranged in upper and lower pairs. The opposite ends of the springs D—D bear respectively on the inner side of the front end wall 18 of the buffing head A and on the forward side of the rear wall 22 of the draft beam C. The lower pair of springs E—E have their front and rear ends bearing respectively on the inner side of the end wall 18 of the buffing head A and on the forward side of the end wall 14 of the supporting member B. In order to maintain the springs E—E properly centered and prevent lateral displacement thereof, both the buffing head and the rear wall of the supporting member B are provided with inwardly projecting bosses, which engage within the coils of the springs, as clearly illustrated in Figure 4. The pair of upper springs D—D are also held in properly centered position by means of rearwardly projecting lugs at the upper end of the front wall 18 of the buffing head A. All the springs D—D and E—E are preferably under slight initial compression when the parts are assembled.

The coupling link F is connected to the draft beam C by means of a coupling pin 30 extending through the top and bottom arms 23—23 of the draft beam C substantially at the center of said beam. The link F is accommodated between these portions of the arms 23—23, as clearly shown in Figure 5, and extends through an opening 31 provided in the front wall 18 of the buffing head A. The top wall 19 of the buffing head A is slotted longitudinally, as indicated at 32, to accommodate the head of the coupling pin 30 for movement. The top arm 13 of the supporting member B is also provided with an opening 33 in alignment with the opening 32 to accommodate the head of the pin for movement and permit application of the pin to the draft beam C.

The operation of my improved mine car draft rigging is as follows: Upon a buffing shock being transmitted to the buffing head A, the head is forced inwardly toward the car, compressing both pairs of springs D—D and E—E against the rear or end wall 14 of the supporting member B. The upper pair of springs D—D, which bear at their rear ends on the draft beam C, are directly compressed against said beam, which is buttressed on the end wall 14 of the supporting member B. Inward movement of the buffing head A is limited by engagement of the inner ends of the side walls of the head with the front ends of the side walls of the draft beam and also by engagement of the front end walls of the slots 28—28 of the buffing head A with the retaining bolts 29—29. When the buffing force is reduced, the buffing head A is returned to the normal position shown in Figures 3, 4, 5, and 6.

Upon a pulling action being applied to the coupling link F in draft, the beam C will be pulled outwardly away from the car, thereby compressing the pair of springs D—D against the end wall 18 of the buffing head A. During this time, the buffing head A is held stationary by the bolts 29—29 engaging the rear end walls of the slots 28—28 of the head A. Outward movement of the beam C is limited by engagement with the rear ends of the side walls of the buffing head A and by engagement of the rear end walls of the slots 27—27 with the bolts 29—29. Upon reduction of the draft force, the springs D—D will return the draft beam C to the normal position shown in Figures 3, 5, and 6.

From the preceding description taken in connection with the drawings, it will be evident that I have provided a buffing and draft device of exceedingly simple and efficient design, which may be applied as a unit to the end of a mine car. 80 Further, the arrangement of parts, as shown, provides a compact structure wherein the buffing shocks are absorbed by a plurality of springs and the draft shocks are taken care of by a portion only of said springs, thus providing higher shock absorbing capacity in buff than in draft and utilizing a minimum number of shock absorbing springs, thereby reducing the number of parts of the device. 85

Another advantage of my improved design is that the pulling force exerted by the coupling element is applied to the draft beam in such a manner that the pressure on the shock absorbing springs is equally distributed, thereby preventing tilting of the draft beam with respect to the coupling link and other parts of the device and avoiding excessive wear of the parts and adding to the life of the entire mechanism. 90

I have herein shown and described what I now consider the preferred manner of carrying out my invention, but the same is merely illustrative and I contemplate all changes and modifications that come within the scope of the claims appended hereto. 100

I claim:

1. In a draft rigging for cars, the combination with a central buffing head at the end of the car movable inwardly toward the car in buff; of two sets of shock absorbing devices opposing inward movement of the buffing head, one of said sets being disposed above the other; and an outwardly movable draft member actuating one only of said sets of shock absorbing devices in draft. 105

2. In a draft rigging for cars, the combination with a buffing head at the end of the car, said head being movable inwardly toward the car in buff; of a transversely disposed draft beam; coupler means connected centrally of the draft beam and pulling the beam outwardly away from the car in draft; and upper and lower pairs of shock absorbing devices yieldingly opposing movement of the buffing head toward the car, said upper pair of shock absorbing devices also yieldingly opposing outward movement of the draft beam, said lower pair of devices being inactive during draft. 110

3. In a draft rigging for cars, the combination with an inwardly movable center buffing head at the end of the car; of upper and lower pairs of springs yieldingly opposing inward movement of the buffing head; and a transversely disposed pulling member at the corresponding end of the car, said pulling member engaging one of said pairs of springs only to oppose outward movement of the pulling member in a draft action. 115

4. In a draft rigging for cars, the combination with an inwardly movable center buffing head at the end of the car; of upper and lower pairs of springs bearing at their outer ends on said head; fixed abutment means on the corresponding end of the car, on which the inner ends of the lower pair of springs bear; and a transversely disposed beam at said end of the car, said beam being interposed between the abutment means and the upper pair of springs, entirely clearing the lower springs and having engagement with said upper springs only to compress the same in draft, said draft beam being movable away from the car in draft and said buffing head being held 120

against movement with respect to the car in draft.

5. In a draft rigging for cars, the combination with an inwardly movable buffering head at the end of the car; of upper and lower pairs of springs bearing at their outer ends on the inner side of said head; means for limiting outward movement of the buffering head; fixed abutment means on the end of the car on which the inner ends

of one of said pairs of springs bear; and an outwardly movable draft member entirely clearing said last named pair of springs and bearing on the inner ends of the springs of the other pair to actuate said last named pair only, said draft member being interposed between said last named pair of springs and said abutment means.
